TOBACCO SHOWCASE HUMIDIFIER

Domenico Patriarca, Cranston, R. I.

Application January 22, 1953, Serial No. 23,249

Term of patent 14 years

(Cl. D85—7)

To all whom it may concern:

Be it known that I, Domenico Patriarca, a citizen of the United States, residing in the city of Cranston, county of Providence, State of Rhode Island, have invented a new, original, and ornamental Design for a Tobacco Showcase Humidifier, of which the following is a specification, reference being had to the accompanying drawing, forming a part hereof.

The single figure is a perspective view of a tobacco showcase humidifier, showing my new design.

The left hand end view is identical with the right hand end view as shown in the single figure

of the drawing. The back view is substantially the same as the front view as shown in the single figure of the drawing, in that the back view has two louvers the same as the front view.

I claim:

The ornamental design for a tobacco showcase humidifier, as shown and described.

DOMENICO PATRIARCA.
